UNITED STATES PATENT OFFICE.

SAMUEL C. McKEOWN, OF NEWARK, NEW JERSEY, ASSIGNOR TO SPLITDORF ELECTRICAL COMPANY, OF NEWARK, NEW JERSEY.

CIRCUIT BREAKER FOR IGNITION MAGNETOS.

Application filed November 9, 1920. Serial No. 422,787.

To all whom it may concern:

Be it known that I, SAMUEL C. McKeown, a citizen of the United States, residing at Newark, in the county of Essex, 5 State of New Jersey, have invented certain new and useful Improvements in Circuit Breakers for Ignition Magnetos, of which the following is a description, reference being had to the accompanying drawing and 10 to the figures of reference marked thereon.

This invention relates to circuit breakers for ignition magnetos for internal combustion engines and especially to magnetos of the oscillatory type wherein a shaft bearing 15 two lobes of constant polarity oscillates between two stationary pole pieces so that the flux threading the lobes is alternately passed through the pole pieces first in one direction and then in the other. In this type 20 of magneto an induction coil is generally wound about a bridge member joining the two pole pieces. In the electrical circuit of the primary coil is interposed a circuit breaker movable in unison with the engine 25 so as to make and break the circuit at appropriate times. It is the common practice to maintain this circuit closed until just prior to the time of firing a charge within a cylinder, then the circuit is opened, and 30 the induced current in the secondary causes a spark to jump across the spark gap within the cylinders.

It is however a distinct disadvantage in a magneto and particularly in a magneto 35 of the oscillatory type to keep the primary circuit closed during the time when the flux is reversing and increasing. In an oscillatory magneto this flux reversal and increase takes place during the so called cocking operation. As the lobes of the inductor of 40 the magneto oscillate first into flux decreasing position and then into maximum flux threading position, the rate of building up of flux in the desired direction is diminished 45 by the counter magneto motive force generated by the current in the coil of the primary circuit which current tends to maintain the old direction of flux threading the coil. As a consequence when the circuit is 50 opened and there is simultaneously a rapid diminution of the flux threading the coil due to the movement of the lobes from their maximum flux threading position to their minimum flux threading position, the total 55 decrease of the flux and the consequent rate

of change of flux is not as great as it might have been had the flux threading the coil been given the opportunity to build up to a greater magnitude.

It is an object of this invention to construct means whereby the flux may build up to a higher value than has heretofore been possible in magnetos of the type described.

As the speed of the engine increases and the periodicity of the oscillating shaft increases, the disadvantage of having a closed primary circuit as is the common practice becomes more evident, since the time within which the flux is permitted to build up is shortened. It is, therefore, another object 70 of this invention to provide means whereby a higher engine speed may be used and still provide a good spark within the cylinders.

It is a further object of my invention to 75 simplify the construction of the circuit breaker and make the same as of few parts as is consistent with the proper functioning of the machine.

In the application of Leibing, Serial No. 80 312,426 filed July 21, 1919, now Patent 1,461,128, issued July 10, 1923, there is described one means whereby an intensified spark may be obtained. The present application discloses a new and improved means 85 whereby the same result may be gotten.

In the drawings which disclose one embodiment of my invention:

Figure 1 is a view of my circuit interrupter, the magneto magnetic circuit being 90 shown diagrammatically, the parts being in the normal position, the circuit breaker and magneto operator being viewed from different ends of the magneto.

Figure 2 is a somewhat similar view 95 showing the parts at the completion of the cocking operation, the circuit interrupter being closed, and the rotor being about to return for its working stroke.

Figure 3 shows the rotor at the end of 100 its working stroke, the contacts being then opened.

Figure 4 is a perspective view of one of 105 the elements of an interrupter tripping mechanism.

Referring now to the details, wherein like numbers refer to corresponding parts in the various views, 1 and 2 illustrate the field poles of a magnetic field structure across which the core 3 is placed. Core 110

3 is illustrated as having a low tension winding 4 and a high tension winding 5. A spark gap 6 illustrating a plug in an engine cylinder is connected in circuit with 5 the high tension winding 5. The breaker box 7 for attachment to one end of the ignition generator carries a stationary insulated block 8 carrying an adjustable contact 9. A movable member 10 carries a contact 11 10 adapted to cooperate with contact 9. Member 10 is preferably grounded as indicated. Between the field poles 1 and 2 an inductor having lobes 12 and 13 is adapted to operate. This type of inductor and its manner of distributing the flux through the field poles 1 and 2 and core 3 is illustrative of the well known "Dixie" type of ignition generator and since it is well illustrated and described in Patent #1,081,760, issued December 16, 1913, to C. T. Mason, it will not be further described herein except in connection with my arrangement of control of the flux through the working coil. Attached to one end of the operating shaft is a lever 14 which is held in a normal stationary position by springs 15 and 16, all in a well known manner. The lever 14 is adapted to be operated by a movable member 17 driven by the engine. At the other end of 25 the shaft is a member 18 provided with a cam surface 19 adapted to engage a bumper 20 mounted on one end of the movable member and with a second cam surface 21 for a purpose hereinafter described. Within the breaker box 7 there is pivoted as at 22 a catch 23 provided with a lip 24 to engage the end of the movable member carrying the contact and the lip is carved out at 25 so as to fit snugly about the movable contact 11, 30 in order that a good purchase may be had on the movable member 10. It is understood that if the support for the movable contact be made longer that it would not be necessary to carve out the lip 25. A spring 40 26 trained around the pivot 22 normally holds the catch so as to be in locking engagement with the contact member when in its open position and a spring 30 secured to a stud 31 in the breaker box tends to hold the contacts 9 and 11 closed when the movable member is released from the catch. The catch is dished on its under side at 27 and 28 so as to provide a clearance for the member 18, there being an intervening ridge 55 29 between the dished portions 27 and 28 for engagement with the cam surface 21 when the member 18 is oscillated into circuit breaker closing position.

Coming now to the operation of the device and assuming the parts to be in the normal or stationary position shown in Figure 1, it will be noted that the circuit breaker points are held open by means of the catch 23 and that the flux is threading the coil in 60 the direction of the arrows. As the rotor 65

is moved by the member 17 rotating clockwise and acting to the right against lever 14 it is seen that the lobes 12 and 13 as they move counter clockwise toward the position shown in Figure 2 will produce a change 70 of flux tending to set up a current in the primary winding 4. This current would oppose the decrease of flux in one direction and hinder the building up of flux in the opposite direction. But this is obviated by 75 the circuit contacts 9 and 11 being held apart. As the lever 14 reaches the extreme cocked position shown in Figure 2 the cam surface 21 engages the ridge 29 on the catch 23 and the contact member 10 is released permitting the contacts 9 and 11 to close. This completes the so-called cocking operation. It should be noted that all the while that the flux has been reversing and building up that the contacts 9 and 11 were open and hence no hindrance or opposition was offered by the primary coil to the reversal and the building up of the flux. With the parts as shown in Figure 2, the magneto is ready 80 for the working impulse. As the nose of the engine driven member 17 passes from underneath the member 14, the springs 15 and 16 snap the rotor around past the position in Figure 1 to a position as in Figure 3. At this time the catch 23 will hook over the 85 member 10. The rotor then returns quickly to normal position shown in Figure 1. The opening of the primary circuit takes place just after the rotor lobes are leaving the pole pieces, that is, substantially at the time 90 when the maximum flux change takes place.

Having thus described my invention what I claim is:

1. In a circuit breaker for an ignition current generator of the oscillating type, a stationary contact, a movable contact yieldingly urged to closed position, a catch normally latching the movable contact in open position and a member rigidly connected with said oscillatory element, oscillatable to alternately release said catch from contact closing restraining movement and to move said movable contact to latching position.

2. In a circuit breaker for an ignition current generator of the oscillating type, a stationary contact and a movable contact yieldingly held in engagement with the stationary contact, a pivoted member on which the movable contact is mounted, a member rigidly connected with the oscillatory element operable upon movement thereof in one direction to open said contacts, a catch operable to latch said movable member and maintain said contacts open, said member being provided with means to trip said catch upon movement thereof in the opposite direction.

3. In a circuit breaker for an ignition current generator of the oscillating type, a stationary contact, a pivotally mounted mov-

able contact yieldingly held in engagement therewith, a member rigidly connected with the oscillatory element, provided with a cam surface to disengage the contacts, a catch 5 operable upon disengagement of the contacts to latch the movable contact and hold the same open and a second cam on said member operable upon movement of the member to release the catch from contact 10 moving restraining position.

4. In a circuit breaker for an ignition current generator of the oscillating type, a stationary contact and a movable contact, a pivoted member supporting the movable contact, a spring secured to said pivoted member urging the contacts to closed position, a catch cooperating with the movable contact to latch the contacts open, an oscillatable member rigidly connected with the oscillatory element, provided with two cam surfaces, one cam surface acting to open the contacts upon oscillation of the member in one direction and the other cam surface acting to trip the catch to permit the contacts 20 to close upon oscillation of the member in the other direction.

5. In a circuit breaker for an ignition current generator of the oscillating type, a circuit breaker comprising a stationary contact, a movable contact yieldingly urged to closed position, a catch latching the movable contact in open position while the movable oscillatory member is moving so as to reverse the flux in the magnetic circuit and to build 30 the flux up therein in the opposite direction, and means at the end of said movement to trip said catch and close the contacts and means operative on the return movement of said oscillatory member to again open said contacts.

6. In a circuit breaker for an ignition current generator of the oscillating type, a latch for said circuit breaker, said circuit breaker being latched open during a flux reversal in 40 the core of the generator, means to release

said latch at the time of maximum flux threading the core, and means to cause said latch to again engage said circuit breaker immediately after the time of maximum flux change in said core. 50

7. In a circuit breaker for an ignition current generator of the oscillating type, means normally latching the circuit breaker open, a member on the oscillatory element operable upon movement of said element to maximum 55 flux threading position to trip said first named means to permit the circuit breaker to close and means operative to restore the parts to normal position after the time of maximum flux change in said coil. 60

8. In a circuit breaker for an ignition current generator of the oscillating type, a stationary contact, a movable contact yieldingly urged to closed position, a catch normally latching the movable contact in open position, while an oscillatable member is moving in one direction and means actuated by said oscillatable member to release said catch from contact closing restraining movement, and means operative on the return movement of said oscillatable member to again 65 open said contacts. 70

9. In a circuit breaker for an ignition current generator of the oscillating type, a stationary contact and a movable contact, a pivoted member supporting the movable contact, a spring secured to said pivoted member urging the contacts to closed position, a catch cooperating with the movable contact to latch the contacts open, a member actuated by the oscillatable member and provided with two cam surfaces, one cam surface acting to open the contacts upon oscillation of the member in one direction and the other cam surface acting to trip the catch 75 to permit the contacts to close upon oscillation of the member in the other direction. 80

In testimony whereof, I affix my signature.

SAMUEL C. McKEOWN.
